UNITED STATES PATENT OFFICE

105,442

DESIGN FOR A CASKET TABLE FOR HEARSE

Earl L. Schofield, Freeport, Ill., assignor to Henn
ey Motor Company, Freeport, Ill., a corpora
tion of Delaware

Application October 26, 1936, Serial No. 65,519

Term of patent 14 years

To all whom it may concern:

Be it known that I, Earl L. Schofield, a citizen
of the United States, residing at Freeport, in the
county of Stephenson and State of Illinois, have
invented a new, original, and ornamental Design
for a Casket Table for Hearses, of which the
following is a specification, reference being had
to the accompanying drawing forming part
thereof.

In the drawing:

Figure 1 is a schematic plan view of a casket
table for hearses embodying my design;

Fig. 2 is an enlarged plan view of approximately
one-quarter of the table to give a better illus
tration of the design;

Fig. 3 is a side view of Fig. 2, and

Fig. 4 is an end view of the table on the
same scale as Fig. 2.

In Figs. 2, 3 and 4, the stippling indicates con
trasting color.

I claim:

The ornamental design for a casket table for
hearses, substantially as shown and described.

EARL L. SCHOFIELD.
